UNITED STATES PATENT OFFICE.

GEORGE A. GASE, OF CLEVELAND, OHIO, ASSIGNOR, BY MESNE ASSIGNMENTS, TO THE
ICELESS MACHINE COMPANY, OF CLEVELAND, OHIO, A CORPORATION OF OHIO.

GAS-REGULATOR.

1,162,347.

Specification of Letters Patent. Patented Nov. 30, 1915.

Application filed September 3, 1914. Serial No. 859,965.

To all whom it may concern:

Be it known that I, GEORGE A. GASE, a citizen of the United States, residing at Cleveland, in the county of Cuyahoga and 5 State of Ohio, have invented a certain new and useful Improvement in Gas-Regulators, of which the following is a full, clear, and exact description, reference being had to the accompanying drawings.

10 This invention is for a device for regulating a supply of gas or other fluid by means of a valve, the seating of which is opposed by a head of water, the device operating in such a manner that the gas passing through 15 it is accurately controlled to give a constant pressure, while upon the failure of the water the gas or other fluid is shut off.

Another object is to provide a device of such nature which shall be efficient, very simple in construction and have no parts liable to become disarranged or broken.

Another object is to provide a means for causing a uniform pressure of the water acting against the valve so long as any water 25 is being supplied.

The above and other objects will become apparent in the following description in connection with the drawings, and the essential characteristics are hereinafter set forth 30 in the claims.

Referring to the drawings, Figure 1 is a side elevation of my device, being partly broken away to show the valve for the gas and the means for regulating the same; Fig. 35 2 is a plan of the device; Fig. 3 is a vertical transverse section on the line 3—3 of Fig. 2 and Fig. 4 is a similar section on the line 4—4 of Fig. 2.

Referring to the drawings by reference 40 numerals, 5, indicates a chambered base member, preferably a casting, having a passage 6 for water leading to a circular chamber 7. This chamber 7 is in communication with a passage 8 leading to a vertical pipe 9 suitably mounted in a top wall 10 of a chamber formed at the end of this passage. The chamber 7 has a circular opening 12 in its upper wall, closed by a diaphragm 13 clamped in place between this wall and a flange 15 of the valve body 16. The valve body is shown as held to the base by suitable 45 can screws 18. This diaphragm is attached at its center to a vertical valve stem 20, by means of suitable washers 21 and a nut 22, as 50 shown. The valve body is provided with

pipe connections to which are fitted pipes 24 and 25, and the gas or other fluid is supplied through the pipe 24 to a chamber 26 separated from a chamber 27 by a wall 28. This wall is provided with a suitable opening for 60 the passage of gas adapted to be closed by a valve head 30, rigidly mounted on the valve stem 20. At its upper side the chamber 26 is provided with a threaded opening into which is fitted a plug 32 having a short 65 axial bore 33 providing a guide for the upper end of the valve stem. The lower end of the valve stem is guided by passing loosely through the base at the lower wall of the chamber 7.

70 The water is fed to the chambered member 5 through a suitable pipe 35—through the passage 6 to the chamber 7, the passage 8 and upwardly through the pipe 9, overflowing at the open top thereof and returning 75 downwardly outside of the pipe 9, and within a tube 36 mounted in the upper portion of a chamber 38 with which it communicates. This chamber opens into a passage 39 leading downwardly to a suitable exit 80 passage or pipe 40. A vent opening 37 in the pipe 36 allows a free downward flow of water to the exit passages. Thus the column of water within the pipe 9 provides a uniform head or pressure bearing upwardly on 85 the diaphragm 13 to normally hold the valve 30 off of its seat while the water is being supplied to the device. This allows the passage of gas through the pipes 24 and 25. Upon the failure of the supply of the water 90 to the device, the water within the chamber will drain through the opening 44, removing the upward pressure from the diaphragm 13 allowing this diaphragm to resume its normal position under the weight of the valve 95 and stem and the gas pressure on the diaphragm, thereby shutting off the supply of gas. If the pressure of gas flowing through the pipe 25 becomes greater than is desired, such pressure will act downwardly on the 100 diaphragm, closing or partially closing the valve, thereby automatically providing for evenly regulating the flow of gas.

105 Although my device may be adapted for many uses such as the control of the heating gas in water heaters, etc., it is particularly adapted for controlling the heating and cooling media in a refrigerating apparatus of the generator-absorber type and may be used as a substitute for the fuel gas-control- 110

2

ling valve shown and described in the application of Harrison H. Southworth and myself, Serial No. 741,414, filed January 11, 1913. By providing a suitable lever or other mechanism adapted to engage the lower end of the valve stem by means of a collar such as shown at 42, the device may be applied to a refrigerating apparatus such as shown and described in the application of Harrison H. Southworth, No. 837,118, filed March 8, 1914. It is to be understood, however, that I do not wish to be limited to such uses of my device. When applied to a refrigerating apparatus such as shown in the application, the cooling water for the apparatus is supplied through the pipe 35 and overflows through the outlet 40. Upon the failure of this cooling water it is desirable to shut off at once the fuel gas supplied to the burner of the apparatus through the pipes 24 and 25 and the valve 16. It will be seen that this shutting off of the gas would occur immediately upon the failure of the supply of water through this pipe, as the water would drain from the chamber 7, through the guide opening at 44 about the lower end of the valve stem, thereby removing the pressure on the diaphragm allowing the valve to seat itself.

Having thus described my invention, what I claim is:

30 1. In a gas regulator, the combination of a conduit for gas, a valve therein, a diaphragm connected with the valve, a water passageway beneath the diaphragm, an upright tube open at its upper end and connected at its lower portion with the space beneath the diaphragm, an outer casing surrounding the tube and providing an overflow passageway therefor, and conduits for conveying water to the tube and from the outer casing.

35 2. In a gas regulator, the combination of a casing having a valve seat and an opening below the seat and intake and exit passages one above the seat and the other below the seat, a diaphragm across the opening referred to, a chamber for fluid below the diaphragm, a casing communicating with an exit pipe for liquid, an internal upright tube within said casing having an opening at its upper end into the casing and having its lower end in communication with the space beneath the diaphragm, and means for admitting liquid to said space.

40 3. In a gas regulator, the combination of a conduit for gas, a conduit for water, a valve in the gas conduit, a diaphragm between the water and gas conduits, connections between the diaphragm and the valve, a tube providing a water column of sufficient height to

cause the water to raise the valve from its seat, and an outer casing freely surrounding the tube and providing an overflow.

4. In a gas regulator, the combination of a conduit for gas, a conduit for water, a valve in the gas conduit, means whereby the water pressure may act on the valve to raise the same, an internal vertical passage in said water conduit providing a water column causing a pressure of the water on said means, a passage embracing said vertical passage and leading to an exit opening whereby the water may overflow from said water column passage.

5. In a gas regulator, the combination of a gas valve, conduits leading thereto and therefrom, a chambered casing on which said valve is mounted having a passage for water, means in said casing connected with the valve whereby water pressure may raise the valve from its seat, a tube in communication with said water passage providing a water column, a tube outside said tube providing an overflow passage, and an exit opening in communication with said overflow passage.

6. In a gas regulator, the combination of a gas valve, pipe connections leading thereto and therefrom, a casing on which said valve is mounted having a water passage therein, a pipe leading to said water passage, a chamber for the water beneath the valve, a diaphragm closing the upper portion of said chamber, connections between the valve and said diaphragm, a vertical passage connected with the water passage providing a water column above the diaphragm, and a vertical tube outside said first mentioned tube providing an overflow passage around the same.

7. In a gas regulator, the combination of a gas valve, conduits leading thereto and therefrom, a casing on which said valve is mounted having a water passage therein, a conduit leading to said water passage, a chamber for the water beneath the valve, a diaphragm closing the upper portion of said chamber, connections between the valve and said diaphragm, a vertical passage connected with the water passage providing a water column above the diaphragm, a vertical tube outside said passage providing an overflow passage around the same, and exit openings in communication with said overflow passage and said chamber for draining the same.

In testimony whereof, I hereunto affix my signature in the presence of two witnesses.

GEORGE A. GASE.
